UNITED STATES PATENT OFFICE.

CHARLES M. LAMB, OF MONESSEN, PENNSYLVANIA.

WIRE-FABRIC MACHINE.

No. 796,663.

Specification of Letters Patent.

Patented Aug. 8, 1905.

Application filed June 14, 1904. Serial No. 212,450.

To all whom it may concern:

Be it known that I, CHARLES M. LAMB, a citizen of the United States, residing at Monessen, in the county of Westmoreland and State of Pennsylvania, have invented a new and useful Improvement in Wire-Fabric Machines, of which the following is a specification.

My invention relates particularly to machines for making fence comprising strand-wires and stay-wires crossing the same at right angles and secured at the intersections by wrapping about the strand-wires, each stay-wire comprising a single length of wire extending across or practically across the fence.

Leading objects of the invention are, first, to provide a machine capable of operating simultaneously upon different portions of a plurality of stay-wires in forming a fence of the character indicated, thus providing for increased output; second, to provide for a continuous movement of the fence through the machine, thereby still further increasing the capacity for output; third, to provide for the use of uncoiled stay-wires of a length sufficient to extend completely across or nearly across the fence, and, fourth, to provide important improvements in details of construction throughout the machine, as will hereinafter more fully appear.

In the preferred construction, which may be variously modified, as hereinafter suggested, I employ a plurality of rotary longitudinally-reciprocating tubular stay-wire wrappers through which the strand-wires pass and which are equipped with wrapping-heads operating generally between different transverse planes, the first two wrappers operating, however, between the same transverse planes and having opposite motions of rotation in wrapping and like motions of reciprocation and alternate wrappers (commencing with the second one) having like movements of reciprocation and like movements of rotation and the remaining alternate wrappers having like movements opposed to the movements of the first-named alternate wrappers and means for shifting the stay-wires or stays or their successively-unused portions from the initial position thereof, by successive steps, across the strand-wires to bring successive portions of each stay-wire or stay into the grasp of the several wrappers *seriatim*.

To facilitate understanding, it may be stated here that in the machine illustrated in the accompanying drawings the full-length stays lie

after severance from the spool parallel with and adjacent to the near or top strand-wire and are transferred *seriatim* by a slide or stay-wire shifter or stay-shifter from the severing mechanism across the two top strand-wires, an end portion of each stay being bent as it moves in turn at right angles to the main portion thereof. Each stay is in proper turn operated upon by the first two wrappers, which simultaneously wrap the upper extremity of the stay about the top strand-wire and the portion adjacent to the angle in the stay about the second strand-wire, the main portion of the stay lying in a longitudinal channel at one side of the tubular second wrapper and being carried thereby about the second strand-wire. The first two wrappers move forwardly while the wrapping takes place and meet the returning third wrapper, whereupon a second slide operates to shift the unused portion of the stay parallel with itself, paying out, however, enough to cover the space between the second and third strand-wires. This action is repeated on across the machine until the stay has all been paid out and has been wrapped about all the strand-wires. The first shifter operates over two spaces, so that the number of stay-shifters required is equal to the number of strand-wires less one, although one slide may constitute several shifters where the spaces between strand-wires are equal.

My invention is illustrated in its preferred embodiment in the accompanying drawings, in which—

Figure 1 is a plan view of my improved wire-fabric machine; Fig. 2, a broken side elevational view, showing the front portion of the machine; Fig. 3, a broken side elevational view supplementing Fig. 2 and showing the rear portion of the machine with the extreme rear end broken away; Fig. 3^a, an enlarged view further illustrating a detail of the means whereby the feed of the wire from which the stays are formed is intermittently interrupted to permit the stays to be severed, this means being shown in full in Fig. 3; Fig. 4, an enlarged plan view of the rear portion of the machine; Fig. 5, a transverse section taken as indicated at line 5 of Fig. 1 and showing the front ends of the rotary longitudinally-reciprocating stay-wrappers and showing also the means for rotating and reciprocating said wrappers; Fig. 6, a broken vertical longitudinal sectional view taken as indicated at line 6 of Fig. 5; Fig. 7, a transverse vertical section taken as indicated at line 7 of Fig. 1 and

showing the transversely-reciprocating cam and the racks carried therewith, which are employed for reciprocating the wrappers or knotters and rotating the same; Fig. 7^a, a broken transverse section taken as indicated at line 7^a of Fig. 1 and showing a detail of the improved take-up drum employed; Fig. 7^b, a section taken as indicated at line 7^b of Fig. 7^a; Fig. 7^c, a broken plan section taken as indicated at line 7^c of Fig. 7^a; Fig. 8, a plan section taken as indicated at line 8 of Fig. 7; Fig. 9, a broken plan view showing the transversely-reciprocating cam; Fig. 10, a broken transverse section taken as indicated at line 10 of Fig. 9 and showing the means for operating the stay-severing device; Fig. 11, a section longitudinally of the machine and taken as indicated at line 11 of Fig. 10; Fig. 12, a section taken as indicated at line 12 of Fig. 10; Fig. 13, a broken section taken as indicated at line 13 of Fig. 9 and showing the details of adjustable stops employed in connection with the means for reciprocating the stay-wrappers; Fig. 14, a transverse vertical section taken as indicated at line 14 of Fig. 1 and looking toward the rear end of the machine; Fig. 15, a broken longitudinal sectional view taken as indicated at line 15 of Fig. 17 and showing a detail of one of the stay-wrappers and the stay-shifters; Fig. 15^a, a section taken as indicated at line 15^a of Fig. 15 and showing a detail of a wrapper-head or hook employed; Fig. 15^b, a side elevational view of a removable plug employed within the wrapper-head to center the strand-wire, said plug being automatically detached when encountered by a knot in the strand-wire; Fig. 15^c, a section taken as indicated at line 15^c of Fig. 15^a; Fig. 16, a broken plan section taken as indicated at line 16 of Fig. 6 and showing the relative position of the parts after the first stay-shifter has operated to carry the stay across the first two strand-wires, bending one end portion of the stay at right angles to the main portion of the stay and bringing it within the grasp of the hooks of the first two stay-wrappers; Fig. 17, a similar section showing the position of the parts after the first two stay-wrappers have advanced and performed their operations and the first stay-shifter has returned for another stay; Fig. 18, a transverse vertical section taken as indicated at line 18 of Fig. 16, but showing the parts in a different position—viz., in the position which they occupy when the first stay-shifter is about to receive a stay from the stay-severing mechanism and to transfer the same across the first two strand-wires; Fig. 19, a similar section showing the parts in the positions corresponding with the positions shown in Fig. 16; Fig. 20, a longitudinal plan sectional view through the stay-severing mechanism, the section being taken as indicated at line 20 of Fig. 14; Fig. 21, a broken transverse vertical section taken as indicated at line 21 of Fig. 20; Fig. 22, a section taken

as indicated at line 22 of Fig. 20 and showing the stay-severing rotary knife; Fig. 22^a, a section taken as indicated at line 22^a of Fig. 20; Fig. 22^b, a broken section taken as indicated at line 22^b of Fig. 22^a; Fig. 23, a broken transverse vertical section through the machine, taken as indicated at line 23 of Fig. 4 and showing a detail of the means for feeding wire from a spool to the stay-severing mechanism and showing also a detail of endless-chain mechanism equipped with hooks for preventing deflection of the strand-wires from their proper course while the stays are being applied and also for stretching or straightening the stays after they have been applied; Fig. 24, a broken elevational view showing the manner in which one of said hooks engages a strand-wire; Fig. 25, a broken transverse vertical section taken as indicated at line 25 of Fig. 1 and showing a detail of the mechanism employed for imparting a spiral or wavy form to the strand-wires; Fig. 26, a broken longitudinal section taken as indicated at line 26 of Fig. 25; Fig. 27, a section taken as indicated at line 27 of Fig. 26; Fig. 28, a broken view taken as indicated at line 28 of Fig. 4 and showing a tension device for the stay adjacent to the head of the last stay-wrapper; Fig. 29, a perspective view showing the head of the first stay-wrapper; Fig. 30, a perspective view showing the head of an intermediate stay-wrapper; Fig. 31, a perspective view showing the head of the last stay-wrapper; Fig. 32, a side elevational view of the member shown in Fig. 31 looking at the point of the hook; Fig. 33, a view of the hook, taken as indicated at line 33 of Fig. 32; Fig. 34, a view illustrating the first stay-wrapper in the operation of forming the knot at the top or first strand-wire; Fig. 35, a similar view showing the knot completed; Fig. 36, a view showing an intermediate wrapper in process of forming a knot, and Fig. 37 a view showing said knot completed.

A general description of the preferred construction will now be given, and this will be followed by a detailed description of the parts.

A represents the frame of the machine, which may be of any suitable construction; B, a wire-measuring feed-drum at the front end of the frame over which the strand-wires are fed into the machine and which is now of well-known construction; C, improved mechanism for imparting spirals or waves to the strand-wires, which mechanism is located slightly in the rear of the drum B; D, a shaft in the rear of the mechanism C and equipped with a pulley D', through which power is applied to the machine; E, a counter-shaft actuated by a gear E', meshing with a pinion E² on one end of the shaft D, the counter-shaft E serving to transmit power to the several mechanisms of the machine; F, a transversely-reciprocating slide equipped with cams for reciprocating the stay-

wrappers and with racks for rotating the same; G to G¹⁰, inclusive, a series of rotary longitudinally - reciprocating stay - wrappers, the first two wrappers having hooks or heads operating between common transverse planes and having opposite movements of rotation and like movements of reciprocation and the remaining wrappers having hooks occupying successively advanced positions, alternate wrappers, commencing with the second one, having like movements of reciprocation and rotation and the remaining alternate wrappers having like movements of reciprocation and rotation which are opposed to the movements of reciprocation and rotation of the first-named alternate wrappers; H to H⁶, inclusive, a series of transversely-reciprocating slides, each constituting one or more stay-shifters; H⁶, a stationary frame-carried member which serves to engage the rear-end portions of the stays as they are in succession shifted across the first and second wrappers, thereby bending said end portions at right angles to the main portions of the stays; I, a rock-shaft equipped with arms joined by connecting-rods to said slides, said rock-shaft being journaled in suitable bearings at the rear side of the top-portion of the frame; J, severing and feeding mechanism for severing the stays from the spool supplying the same and delivering the same to the first stay-shifter, said mechanism being located at the front side of the top portion of the frame; J', Figs. 3 and 4, mechanism for feeding wire from a spool J² to the knives of the mechanism J; K, endless-chain mechanism serving to maintain the fence in proper position in its passage through the machine and serving also to stretch and straighten the stay-wires; L, a drum over which the fence passes on its way to the take-up drum, and M an improved take-up drum journaled in the rear end of the frame.

Power is communicated from the shaft E to the shaft of the drum B through the medium of suitable sprocket-wheels connected by a sprocket-chain a; from the shaft E to the transversely-reciprocating slide F by means of bevel-gears a' and a short longitudinal shaft a², Fig. 7, equipped with a crank a³; from the shaft E to the shaft of the take-up drum M through the medium of pulleys connected by a belt a'; from the shaft E to a short transverse shaft a⁶, Figs. 3 and 7, through the medium of sprocket-wheels connected by a sprocket-chain a⁶, and from the shaft E through the medium of sprocket-wheels and a sprocket-chain a⁷ to a short transverse shaft a⁸, which actuates the mechanism C. Power is transmitted from the shaft a⁵ through the medium of sprocket-wheels and a link belt a⁹, Fig. 4, to the drum L, the endless-chain mechanism K being actuated from the shaft of the drum L, and from the shaft a⁵ through the medium of bevel-gears a¹⁰ and shaft a¹¹, Figs. 3 and 7, and bevel-gears a¹² to a transverse shaft a¹³, which serves to drive the wire-feed-

ing means for supplying the wire from which the stays are formed. The shaft a⁵ is, furthermore, equipped with a cam a¹⁴, Figs. 3, 7, and 14, which serves to actuate a link a¹⁵, connected with a short arm a¹⁶ on the rock-shaft I. Said shaft is also equipped with a balance-wheel a¹⁷.

The frame A preferably comprises suitable transverse members A', Fig. 5, longitudinal I-beams A² for the front portion of the frame joined by cross members supported thereon, Fig. 1, longitudinal I-beams A³, forming the side members of the main portion of the frame, transverse frame members A⁴, constituting a guide for the slide F, a series of transverse members A⁵, Fig. 4, affording bearings for the transversely - reciprocating slides which comprise the stay-shifters, transversely-extending bars A⁶, coacting with said frame members and serving to hold said slides in place, and suitably-connected longitudinal frame members A⁷, Figs. 1 and 3, in which is journaled the take-up drum M.

The measuring-drum B is now well understood in its details of construction and need not be further described herein.

The construction of the mechanism C is shown in detail in Figs. 2, 25, 26, and 27. There are two transverse frame members c c', supported on the I-beams A², as shown in Fig. 1. On these members are journaled a series of shafts c², which are equipped with sprocket-wheels c³. The shafts are actuated through the medium of said sprocket-wheels by means of the sprocket-chain c⁴, passing over idlers c⁵, supported from the frame members c' by short standards c⁶, which have bolt connection with a slot c⁷ in said frame member, permitting adjustment. The standards themselves are adjustable vertically upon their bolts. The sprocket-chain passes about sprocket-wheels c⁸ c⁹ c¹⁰ c¹¹, as shown in Fig. 25. The sprocket-wheel c¹¹ is on a shaft c¹² parallel with the shafts c², said shaft c¹² being equipped with a bevel-gear c¹³, meshing with a bevel-gear c¹⁴ on the shaft a⁸, as shown in Fig. 1. Thus the shafts c² are operated through the medium of the chain a⁷ and the shaft a⁸. Each shaft c² is tubular to receive a strand-wire and has its portion between bearings cut away and suitably bent to enable grooved rollers c¹⁵ c¹⁶ c¹⁷ c¹⁸, having their axes at angles of substantially ninety degrees to each other, to be applied as shown in Fig. 26. The rollers are journaled on studs c¹⁹, adjustable in slots c²⁰, as shown in Fig. 27. It will now be understood that as a strand-wire passes through one of the shafts c² and about the rollers carried thereby the shaft rotating as indicated produces a spiral or wave in the strand-wire.

The shaft D is journaled in bearings d d', supported on the I-beams A².

The shaft E is journaled in bearings e e', supported on the I-beams A².

The slide F comprises, Figs. 5 to 13, inclusive, an upper member f, Figs. 6 and 7, a lower member f', and end spacing members f² f³. From the lower member depends a bracket f⁴, comprising a cam-slot in which the crank d⁵ works. Attached to the upper surface of the upper member f is a pair of adjustable cams f⁵, and attached to the lower surface of the bottom member f' is a pair of adjustable cams f⁶. These cams have slots which extend in a general transverse direction with relation to the machine, but are somewhat oblique with relation to the longitudinal axis of the machine. The obliquity of the upper set of cams is opposed to the obliquity of the lower set of cams, as is indicated in Fig. 9. Working in the upper set of cams are rollers f⁷, depending from longitudinally-extending slide-bars f⁸, which move in guides f¹⁰. The front ends of the slide-bars f⁸ are connected by a transverse member f¹¹, from which depend suitably-spaced bearings f¹² for the front ends of the tubular shafts of the wrappers G, G³, G⁵, G⁷, and G⁹. Working in the slots of the cams f⁶ are rollers f¹³, journaled on upwardly-projecting studs f¹⁴, attached to longitudinally-reciprocating slide-bars f¹⁵, working in guides f¹⁶. The front ends of the slide-bars f¹⁵ are joined by a cross member f¹⁷, with which are connected upwardly-projecting blocks or bearings f¹⁸ for the front ends of the shafts of the stay-wrappers G² G⁴ G⁶ G⁸ G¹⁰. The front ends of the slide-bars f⁸ have adjustably connected therewith by a detail of construction shown in Fig. 13 Z-shaped clips f¹⁹, constituting stops which coact with resilient washers f²⁰ at the front surface of the frame member A⁴. Similarly the front ends of the slide-bars f¹⁵ are equipped with adjustable clips f²¹, which coact with yielding washers f²². These washers are retained by pins, as shown, and may be replaced as required. The cross frame members A⁴ are provided at their lower portions with inturned flanges f²³, upon which the slide F rests, and the members A⁴ therefore form a guide for the slide F. The upper member f of the slide F is equipped on the front half of its lower surface with a rack f²⁴, and the lower member f' is equipped on the rear half of its upper surface with a rack f²⁵. The cams f⁵ and f⁶ are adjustable upon their respective plates f, f' by a detail of construction shown in Fig. 9. Each cam, which is cast separately from its plate, is provided at its ends with a short projecting stem f²⁶, which is adjustable transversely of the plate by means of set-screws f²⁷, between which the stem lies, and against the ends of the stems bear set-screws f²⁸. The set-screws pass through suitable lugs on the outer surfaces of the plates and are suitably secured against jarring loose. Rollers f²⁹, journaled in bearings f³⁰ upon the frame members A⁴, serve to confine the slide F against the flanges f²³.

The cam-slots are so shaped as to give a comparatively fast movement of reciprocation to the stay-wrappers to compensate for the loss which occurs during shifting of the stays and then to cause a slower advance of the wrappers to produce spreading of the knot on the strand-wire and finally to give a faster advance to cause the stay to wrap on itself, as illustrated in Figs. 34 to 37, inclusive.

The stay-wrappers G to G¹⁰, inclusive, comprise shafts of successively-increasing length, with the exception of the first two shafts, which are of the same length. Each shaft comprises two members joined by a coupling-sleeve g, as shown in Fig. 8. The front portions of the shafts of alternate wrappers, commencing with G', are equipped with pinions g', which mesh with the rack f²⁵. Alternate spindles or shafts of the wrappers, commencing with G² and ending with G⁸, are equipped with pinions g², meshing with the rack f²⁴. The spindle of the wrapper G' is equipped with a gear g³, meshing with a pinion g⁴ on the spindle of the wrapper G, whereby the wrapper G is given a faster rotation than the wrapper G' and in the opposite direction. The spindle of the wrapper G⁹ is equipped with a gear g⁵, meshing with a pinion g⁶ on the spindle of the wrapper G¹⁰, whereby the wrapper G¹⁰ is given a faster rotation than the wrapper G⁹. All the intermediate wrappers have the same rate of rotation. The spindles are provided with collars engaging the bearing-blocks f¹² f¹⁸, so that the spindles are reciprocated through the medium of said bearing-blocks. The wrapper G has a head g⁷, Fig. 29, equipped with a hook or wire bearing g⁸, adapted to wind an end of the stay in one direction about the first or top strand-wire. The intermediate wrappers are equipped with heads g⁹, provided with hooks g¹⁰, adapted to wrap the stay in the direction opposite the direction in which the hook g⁸ operates, and the last wrapper G¹⁰ is equipped with a head g¹¹, provided with a hook g¹², adapted to wrap the wire in the same direction as does the hook g¹⁰. Each wrapper-head is tubular and is provided with a withdrawable perforate plug g¹³, as shown in detail in Figs. 15 to 15^c, inclusive. The plug is provided with a removable sector g¹⁴, which is cut out of the block between substantially radial planes and equipped with a lug g¹⁵, working in a radial slot g¹⁶ in the body of the plug. This arrangement permits the strand-wire to be inserted from the side of the plug. The plug has a circumferential groove g¹⁷, and the wrapper-head is provided with a series of perforations g¹⁸ tangential to the bottom of the groove g¹⁷ and into any one of which a wooden pin g¹⁹ may be driven to removably secure the centering-block in place. Each wrapping-head is suitably undercut at the base of its hook to enable the hook to take hold upon the stay. Each head is provided adjacent to the base of

the inner side of its hook with a transverse groove g^{20} to enable the hook of the appropriate shifter to cross and bring the stay within the grasp of the hook. Each wrapper-head except the first one is provided in substantial alinement with one surface of this hook with a longitudinal groove g^{21} for accommodating that portion of the stay which lies parallel with the strand-wire during the wrapping operation. The spindle of each wrapper has splined thereon a plurality of short sleeves or perforate disks g^{22} , having at one side a longitudinally-extending groove or notch g^{23} in substantial alinement with the longitudinal groove in the wrapper-head. These short sleeves, which may be termed "rotary stay-carriers," are journaled near the upper edges of raised bar-form portions g^{24} of certain of the cross-frame members A^5 , as shown in Figs. 8 and 14, their bearings being open at the top, so that the sleeves project slightly thereabove. The sleeves are held against longitudinal movement, while the spindles upon which they are splined reciprocate longitudinally by means of plates g^{25} , which plates are provided with openings of somewhat less diameter than the outside diameter of the sleeves, as shown in Fig. 15. The several wrapper-spindles should be equipped with said sleeves in sufficient number to receive the successively-unused portions of the stays which lie parallel with the spindles, thereby insuring the proper carriage of the stays around the strand-wires during the knotting operations. The raised portions g^{24} of such of the cross members A^5 as are equipped therewith are located between the appropriate longitudinal planes to afford bearings for the rotary stay-carriers, and usually the near ends of the plates g^{25} project beyond the adjacent portions of the parts g^{24} and have downturned points g^{26} , which receive the unused portions of the stays from the rotary carriers when the stay-shifters operate to shift the stays from the rotary carriers of one wrapper to the rotary carriers of the next wrapper.

The slides of the H series are respectively joined, by pairs of connecting-rods h , h' , h^2 , h^3 , h^4 , and h^5 , to the arms h^6 on the rock-shaft I, the members of each pair of arms being of appropriate length to give to the corresponding slide the desired range of movement. Each slide comprises a longitudinal bar h^7 , to which the corresponding connecting-rods are joined, and a series of blocks h^8 , which slide upon the portions g^{24} of the frame members A^5 and are provided with downturned flanges h^9 , which overlap the upper margins of the plates g^{25} . Where the series of blocks attached to a bar comprises a single stay-shifter said blocks are provided at their flanges with a set of notches h^{10} , extending longitudinally of the machine and transversely of said blocks, and where a series of blocks attached to a bar constitute a compound

shifter said blocks are provided with two or more series of alined notches h^{10} , the number of series of notches depending upon the number of stays which are to be shifted by the slide. In Fig. 14, for instance, there are shown three slides each provided with a series of notches and a fourth block provided with two series of notches. As has been pointed out, a single slide may be employed for shifting two or more stays where there are uniform spaces between strand-wires. The notches h^{10} may be brought into registration with the grooves g^{23} of the rotary stay-carriers to enable the shifters to engage the unused portions of the stays and shift the stays. The movements of the parts are so timed that the slides are in position to receive the stays at the moment that the stays are ready to be transferred. Corresponding with what may be termed the "hook" formed at the notch h^{10} of each rearmost block of each shifter is a hook h^{11} , adapted to coact with the blocks of the wrapper-heads, each hook standing out a short distance in advance of its block, as will be understood from Fig. 17. As shown in Figs. 15 and 18, there is provided adjacent to the head of each stay-wrapper a stationary tension-ring h^{12} , having its top portion removed, and this tension-ring is supplemented by a cap portion h^{13} , carried by the corresponding block h^8 . When the block h^8 is in place over the bearing of the wrapper-spindle, the tension-ring acts to bend the strand-wire, as shown somewhat exaggeratedly in Fig. 15. At the last wrapper-head a somewhat different form of tension-ring is provided, as shown in Fig. 28. Here the tension-ring h^{14} bears its own top or cap h^{15} and is cut away at h^{16} to permit the stay to enter. As shown in this figure also, the last series of blocks h^8 have their flanges cut away, as indicated at h^{17} , to enable the last wrapper to carry its stay around its strand-wire while the last shifter is returning to secure a fresh stay. The inside diameters of the tension-rings should of course be small enough with relation to the diameter of the wrapper-heads and the rotary stay-carriers to give the desired tension on the stays.

The shaft I is journaled in bearings i , with which certain of the transverse frame members A^5 are provided near their rear ends, as will appear from Fig. 4.

Referring more particularly to Figs. 4, 8, 17, and 20 to 22^b, inclusive, the mechanism J, which serves to sever the stays from the spool supplying the same and deliver the same to the first of the stay-shifters, comprises a longitudinally-extending shaft j , provided circumferentially with longitudinal grooves j' , the shaft being journaled in bearings j^2 , Fig. 20, a guard j^3 , Fig. 22^a, grooved at its front side to receive the rear portion of the shaft j , a reduced portion or stem j^4 , Fig. 8, extending forwardly from the front end of the main

portion of the shaft and equipped at its front end with a four-sided actuating-head j^5 , Figs. 10 to 12, inclusive, which is notched near its four corners to permit a pawl j^6 , carried by the slide F, to engage it and turn the shaft j a quarter-revolution at each full reciprocation of the slide, a cutter-head j^7 , Figs. 20 and 22, applied to a squared reduced portion of the shaft j near the rear end thereof, a longitudinally-adjustable bearing-block j^8 , Figs. 3 and 20, through which a round reduced rear end portion of the shaft j extends, which reduced portion is equipped at the rear end of the bearing with nuts, as shown in Fig. 20, and a tempered cutting member j^9 , coacting with the cutter j^7 . The bearing j^8 is provided with a perforation j^{10} and the cutting member j^9 is perforated and set into the bearing-block j^8 in alinement with the perforation j^{10} . The wire for forming the stays is fed to the perforation j^{10} through a tube j^{11} . At proper intervals the shaft j is provided with circumferential grooves j^{12} , which serve to receive the flanges of the blocks and the hook of the first stay-shifter. The shaft j is shown provided with four of the longitudinal grooves j' ; but it is obvious that as many grooves may be provided as desired. While the shaft is stationary the wire is fed into the groove thereof which happens to be in alinement with the perforation j^{10} of the bearing-block j^8 , and when the shaft is next revolved the wire is severed and the stay carried upwardly into a position to be engaged by the first stay-shifter, as shown in Fig. 22^a. The front ends of the plates g^2 , which reach the shaft j , are provided with downwardly-curved projections j^{13} , which insure the stay passing properly onto the cross members of the frame when the first stay-shifter operates to transfer the stay from the severing mechanism across the first two strand-wires. Where the transverse circumferential grooves j^{12} occur in the shaft j , the grooves j' are provided with bell-shaped ends j^{14} to insure the entrance of the wire which is to be fed in for forming the stay.

The mechanism J', which serves to deliver the stay-forming wire from the spool J², will be understood by reference to Figs. 3, 4, and 23. It comprises a gear-wheel j^{15} , secured on the near end of the shaft a^{13} to rotate therewith, an idler j^{16} , a change-gear j^{17} , journaled on a stud j^{18} , adjustable in a curved slot j^{19} of a frame member j^{20} , a gear j^{21} , meshing with the gear j^{17} and secured to the near end of a short shaft j^{22} , a gear j^{23} , secured on the shaft j^{22} , pinions j^{24} j^{25} , meshing with the gear j^{23} and secured on short shafts j^{26} , equipped at their inner ends with grooved feed-wheels j^{27} j^{28} and gears j^{29} , meshing with the gears j^{24} j^{25} and secured on short shafts j^{30} , equipped at their inner ends with feed-wheels j^{31} , coacting with the feed-wheels j^{27} j^{28} . As shown in Fig. 23, the bearings for the shafts j^{26} are

pivotedly supported on horizontal pins j^{32} , extending longitudinally of the machine. The bearings are yieldingly held by means of set-screws j^{33} , bearing upon plates j^{34} which in turn bear against rubber blocks j^{35} , resting against the bearings. This arrangement enables the grip of the feed-wheels upon the stay-forming wire to be adjusted as desired. As appears from Figs. 3 and 3^a, the gear j^{15} has a number of its teeth cut away at j^{36} and is equipped adjacent to this point at its near side with a tooth j^{37} , while the gear j^{16} is equipped at its near side with a member j^{38} , provided with rollers j^{39} , coacting with the tooth j^{37} . The purpose of this arrangement is to permit the gear-wheel j^{16} to stand still at intervals while the gear j^{15} continues to rotate, so that the feed of the stay-forming wire is interrupted at regular intervals to permit the stays to be severed and rotated into position to be engaged by the first stay-shifter. In the arrangement shown the gear j^{15} gains over the gear j^{16} at each revolution of the large gear the space of two teeth. The wire 13 from which the stays are formed passes over a wheel j^{40} and through a straightener j^{41} on its way to the feed-wheels j^{28} j^{29} , as shown in Fig. 4.

The construction of the mechanism K for preventing the near strand-wires from being drawn toward the far side of the machine in the operation of the machine and for straightening the stays after they have been applied to the strand-wires will be understood by reference to Figs. 3 and 4, 21 and 23.

The shaft of the drum L is equipped at its near end with a gear l , which meshes with a gear l' on a transversely-extending shaft l^2 . The shaft l^2 is equipped near its ends with sprocket-wheels l^3 l^4 . A relatively long endless chain l^5 passes about the sprocket-wheel l^3 and a sprocket-wheel l^6 , attached to a stub-shaft l^7 , supported in a bearing l^8 , which is adjustable longitudinally of the machine, as shown in Fig. 4. A relatively short sprocket-chain l^9 passes about the sprocket-wheel l^4 and a sprocket-wheel l^{10} , fixed to a shaft l^{11} , journaled in a bearing l^{12} . The sprocket-chains are equipped with bifurcated hooks l^{13} , as shown in Fig. 24. The chains are equipped at intervals with downwardly-projecting studs equipped with rollers l^{14} , which engage the outer surfaces of longitudinal cams l^{15} l^{16} . The cams l^{15} l^{16} have outward swells or curves l^{17} , which serve to spread the chains, and thereby stretch or straighten the stays before the fence passes over the drum L. The endless chains are disposed above the cams, and the lower portions of the chains move rearwardly at the same rate of speed as does the fence, the hooks upon the chains being so disposed as to point downwardly at the lower portions of the chains. The hooks are so spaced that the bifurcations embrace the stays, as shown in Fig. 24.

The take-up drum M comprises, as shown in Figs. 1 and 7^a to 7^c, inclusive, a transversely-extending shaft m, journaled in bearings m¹ m², said shaft being equipped near the bearing m² with a universal joint m³, a plurality of cylinder-sections m⁴, extending parallel with the shaft m, a fixed spider or sleeve m⁵, with which the far ends of the sections m⁴ are connected by pivots m⁶, a shiftable spider or sleeve m⁷, to which the near ends of the sections m⁴ are joined by links m⁸, an angular hand-lever m⁹, having a bifurcated end joined by a pivot m¹⁰ to the shaft m, links m¹¹, connecting said lever with the sleeve m⁷, a rock-shaft m¹², located in a recess in one of the sections m⁴ and equipped with a series of hooks m¹³ for receiving the loops of the strand-wires, and a handle m¹⁴, having a stem passing slidably through a perforation in one end of the rock-shaft m¹² and equipped at its lower end with a head m¹⁵, adapted to enter a socket m¹⁶, with which the shaft m is equipped. When the machine is in operation, the handle m¹⁴ serves to lock the rock-shaft m¹² in position, with its hooks projecting, as shown in full lines in Fig. 7^b. When it is desired to remove a roll of fence from the drum M, the handle m¹⁴ may be turned to release the head m¹⁵ from its socket. The handle may then be moved longitudinally to withdraw said head from its socket, and the handle may then be turned to actuate the rock-shaft and withdraw the hooks to the position shown in dotted lines in Fig. 7^b. The lever m⁹ may then be actuated to collapse the drum and permit withdrawal of the fence. As shown in Fig. 1, the bearing m² is an open bearing, which will permit the drum to be swung upwardly and backwardly about its universal joint to enable the fence to be removed.

The operation will be understood readily from the foregoing detailed description. The strand-wires (designated by the numerals 1 to 11, inclusive) are fed into the machine from spools or reels, (not shown,) passing first about the drum B, then through the coilers C, then through the tubular stay-wrappers, then over the drum L, and finally onto the take-up drum M, upon which the completed fence is wound. Power is applied to the pulley D' and communicated to the counter-shaft E and thence to the several mechanisms of the machine. The strand-wires have an uninterrupted feed, and the stay-wrappers accordingly advance with the strand-wires while the wrapping or knotting operations take place. One set of wrappers, comprising the first, second, and every alternate wrapper thereafter, advance together, while a second set, comprising the remaining wrappers, recede, and vice versa. The stays 12 are cut from the wire supplying them, the feed of said wire being interrupted at intervals to enable the rotary knife to operate and bring a fresh groove into alignment with the supply-wire. Prior to the advance

of the first set of wrappers the shifters for transferring the stays thereto occupy the position shown in Figs. 1, 4, and 17, being ready to transfer stays (or the successively unused portions thereof) from the shaft D across the first two wrappers, from the second wrapper to the third wrapper, from the fourth wrapper to the fifth wrapper, and so on across the machine. Thus upon the operation of the shifters, after the machine is fairly in operation, five stays may be simultaneously shifted, and during the advance of the first set of wrappers six knots simultaneously formed. At the conclusion of the advance of the first set of wrappers the hooks thereof and the hooks of the remaining set of wrappers (just concluding their return movement) meet in pairs, and thereupon the shifters operate to make the transfers just mentioned, the shifters returning immediately to their normal position nearest the front side of the machine. The second set of wrappers in the meantime begin their advance, while the first set recede, at the completion of which movement the hooks of the wrappers, commencing with the third, meet in new pairs. Thereupon the shifters operate to carry stays from the mechanism J across the first and second wrappers, from the third to the fourth wrapper, from the fifth to the sixth wrapper, and so on across the machine. In Fig. 16 this last-mentioned shifting operation is shown completed.

As will be understood from Figs. 3 and 18, the member H⁶, over which the stays are bent as the shifter operates, is undercut at its near edge and its front side, affording beveled surfaces which tend to prevent the stay from slipping up over the top of said member. After the first shifter operates it leaves the angle of the stay in position to be engaged by the hook g¹⁰ of the second wrapper and the transversely-extending near end portion of the stay in position to be engaged by the hook g⁸ of the first wrapper. Since the first and second wrappers rotate in opposite directions, the near end of the stay is wrapped about the first strand-wire, while the main portion of the stay is carried bodily about the second strand-wire, the stay being paid out automatically from its rotary carriers, the tension device h¹² operating to regulate the closeness of the wrap. As before stated, the first and second wrappers move forwardly while performing the wrapping operations and when they reach their extreme advanced positions meet the returning third wrapper, whereupon the shifters operate as already described. Wrapping of the stay upon itself in forming the knot is caused by the change in rate of speed of advance produced by the peculiar shape of the cams with which the slide F is provided, as already described. For the intermediate knots no difficulty is experienced in maintaining the desired tension upon the stays during the wrapping opera-

tions. At the outer strand-wires, however, it is more difficult to maintain the desired tension, and this is compensated for in a satisfactory manner by "speeding up" the two marginal wrappers, as above mentioned. While the stay is being knotted upon the first and second strand-wires there is no tendency for the strand-wires to be drawn out of alinement, and before the third wrapper begins its operation the marginal strand-wire is brought within the grip of the grappling-hooks of the endless chain $\mathcal{I}$, which serves to prevent the strand-wires from being drawn from their proper course thereafter.

While it is preferred to give to the wrappers the longitudinal movement of reciprocation described, thereby rendering possible an uninterrupted feed of the strand-wires through the machine, it will be understood that this feature of the machine may be dispensed with while still retaining advantages incident to the application of a plurality of stays (preferably straight) in the manufacture of a fence of the character to which the present invention pertains. It will be noted that when the wrappers are given a longitudinal movement of reciprocation the stays are advanced by the wrappers themselves, and hence the shifters require only a transverse movement in order to bring the successively-unused portion of each stay within the grasp of the successive wrappers.

While my improved machine was designed primarily for use in the manufacture of fence having continuous stays extending from one margin to the other margin, it will be understood that it would be within the spirit of my invention to apply stays in substantially the manner shown, even though certain of the stays were shorter than the others. Moreover, a fence of the character above described may have applied to it one or more top wires whose stays have slip connection with the stays of the main body of the fence in a manner now well understood in the art, and I desire it to be understood that means for applying one or more strand-wires to the top of a fence by means of connections of the character last indicated may be employed in connection with my improved machine as an improvement thereon, but without departure from my invention.

While I have shown a machine for making a single panel of fence, it will be understood that the number may be extended as desired and simultaneously form two or more fences in the same machine. Moreover, any desired number of wrappers may be employed and the machine given a capacity for forming a fence with as many or as few strand-wires as desired.

It may be here remarked that the feature of having the frame-surface upon which the stays slide in the shifting operations horizon-

tal and the stay-wrappers arranged in a horizontal plane, while advantageous, is not indispensable. A feature which is regarded as of considerable importance also is that of the channels in the shifters which are complementary to the channels in the rotary stay-carriers with which the stay-wrappers are provided, the rotary carriers projecting above the guide-surface of the frame upon which the stays slide. As is probably fully understood, said rotary stay-carriers stop for an instant after the knots are formed, say, by three rotations of the wrappers in position to permit the shifters to draw the stays out of said channels onto the guide-surface of the frame.

Many changes in details of construction within the spirit of my invention may be made. Hence no undue limitation should be understood from the foregoing detailed description, which has been given for clearness of understanding.

What I regard as new, and desire to secure by Letters Patent, is—

1. In a machine of the character set forth, the combination with means for feeding a plurality of strand-wires, of means for supplying substantially straight stays parallel with a marginal strand-wire, rotary wrappers having their operative ends spaced to correspond with spaces between stays, and shifters operative to transfer the successively-unused portions of the stays from strand-wire to strand-wire, for the purpose set forth.

2. In a machine of the character set forth, the combination with means for feeding a plurality of strand-wires, of means for simultaneously operating upon a plurality of stays, comprising mechanism for advancing and wrapping the stays, and including a plurality of stay-wrappers having wrapping ends disposed to operate between successively-advanced transverse planes upon successive portions of the several stays.

3. In a machine of the character set forth, the combination with means for feeding a plurality of strand-wires, of means for simultaneously operating upon a plurality of stays, comprising mechanism for advancing and wrapping the stays, and including a plurality of stay-wrappers having wrapping ends disposed to operate between successively-advanced transverse planes upon successive portions of the several stays, and stay-shifters serving to shift the successively-unused straight portions of the stays from strand-wire to strand-wire and pay out the stays to cause them to span the spaces, said shifters operating to bring the successive portions of the stays into the grasp of the successive wrappers.

4. In a machine of the character set forth, the combination with means for feeding a plurality of strand-wires, means for delivering

wire from a spool into a position parallel with and adjacent to a marginal strand-wire and severing the wire for forming the stays, a plurality of stay-wrappers having successively-advanced operative ends, and a plurality of shifters operative to transfer the successively-unused portions of the stays from wrapper to wrapper and pay out the stays as necessary to enable them to span the spaces between strand-wires and form the knots, for the purpose set forth.

5. In a machine of the character set forth, the combination with means for feeding a plurality of strand-wires, of a plurality of wrappers having longitudinal passages for the strand-wires, means for delivering stays substantially parallel with the strand-wires and attaching an end of each stay in turn to a marginal strand-wire, and means for shifting the successively-unused portions of the stays step by step across the strand-wires and permitting the stays to pay out, the operative end of each wrapper acting in proper sequence at the angle of each stay to wrap the stay about the corresponding strand-wire, the intermediate wrappers being equipped with rotary stay-carrying means, for the purpose set forth.

6. In a machine of the character described, the combination with strand-wire-feeding mechanism, of a plurality of wrappers, means for supplying straight stays substantially parallel with and adjacent to a marginal wrapper, a shifter operating to transfer the stay across said marginal wrapper, means coöperating with said shifter for bending an end portion of the stay to cause it to lie across the marginal strand-wire, and additional shifters operative to transfer the successively-unused portions of the stays from strand-wire to strand-wire, for the purpose set forth.

7. In a machine of the character described, the combination with strand-wire-feeding mechanism, of a pair of oppositely-rotating wrappers having coöoperative ends lying in substantially the same transverse plane, a plurality of additional wrappers having operative ends working between successively-advanced transverse planes, means for supplying stays parallel with and adjacent to the first wrapper, a shifter operative to transfer the stays across the first two wrappers, means coöperating with said shifter to bend the stays as they are transferred in turn by said shifter, and additional shifters operative to convey the successively-unused portions of the stays from strand-wire to strand-wire and bring the angle of each stay in proper sequence within the reach of each successive wrapper, for the purpose set forth.

8. In a machine of the character described, the combination with strand-wire-feeding mechanism, of a plurality of rotary reciprocating stay-wrappers equipped with means

for wrapping the stays about the strand-wires during the advance movement of the wrappers, for the purpose set forth.

9. In a machine of the character described, the combination with strand-wire-feeding mechanism, of a plurality of rotary alternately advancing and receding stay-wrappers equipped with means for wrapping the stays about the strand-wires during the advance movements of the wrappers, for the purpose set forth.

10. In a machine of the character described, the combination with strand-wire-feeding mechanism, of a plurality of rotary reciprocating stay-wrappers, and stay-shifters operating to transfer the successively-unused portions of the stays from strand-wire to strand-wire, for the purpose set forth.

11. In a machine of the character set forth, the combination with strand-wire-feeding mechanism, of a plurality of stay-wrappers having operative ends working between successively-advanced transverse planes, means for rotating said wrappers, and means for reciprocating said wrappers.

12. In a machine of the character set forth, the combination with strand-wire-feeding mechanism, of a plurality of rotary reciprocating stay-wrappers comprising two sets of wrappers, one set consisting of a marginal wrapper and a wrapper adjacent thereto and alternate wrappers thereafter, and the other set consisting of the remaining alternate wrappers, the first set of wrappers having movements of reciprocation opposed to the movements of reciprocation of the second set of wrappers, for the purpose set forth.

13. In a machine of the character set forth, the combination with strand-wire-feeding mechanism, of a plurality of rotary reciprocating stay-wrappers comprising two sets of wrappers, one set consisting of a marginal wrapper and a wrapper adjacent thereto, and alternate wrappers thereafter, and the other set consisting of the remaining alternate wrappers, the first set of wrappers having movements of reciprocation opposed to the movements of reciprocation of the second set of wrappers, the first two wrappers having operative ends working between the same transverse planes and the remaining wrappers of the same set having operative ends working between successively-advanced transverse planes, and the wrappers of the remaining set having operative ends working between successively-advanced transverse planes alternating with the planes between which the wrappers of the first set work, for the purpose set forth.

14. In a machine of the character set forth, the combination with strand-wire-feeding mechanism, of a plurality of stay-wrappers operating in succession upon the successively-unused portions of the stays, beginning with

one end of each stay, and means for maintaining the strand-wires in their proper courses during the movement thereof through the machine, for the purpose set forth.

15. In a machine of the character set forth, the combination with strand-wire-feeding mechanism acting uninterruptedly in feeding the strand-wires, of a plurality of rotary reciprocating stay-wrappers operating in succession upon the successively-unused portions of the stays, beginning with one end of each stay, and means for maintaining the strand-wires in their proper courses during the movement thereof through the machine, for the purpose set forth.

16. In a machine of the character set forth, the combination with strand-wire-feeding mechanism acting uninterruptedly in feeding the strand-wires, of a plurality of rotary reciprocating stay-wrappers operating in succession upon the successively-unused portions of the stays, beginning with one end of each stay, means for maintaining the strand-wires in their proper courses during the movement thereof through the machine, and stay-shifters operating in succession upon the successively-unused portions of the stays, for the purpose set forth.

17. In a machine of the character set forth, the combination with strand-wire-feeding mechanism, of a plurality of revolute stay-wrappers having passages for the strand-wires and equipped with pinions, and a transversely-reciprocating slide equipped with a rack engaging said pinions and serving through the medium thereof to rotate said wrappers.

18. In a machine of the character set forth, the combination with strand-wire-feeding mechanism, of a plurality of wrappers having passages for the strand-wires and equipped with pinions fixed thereon, and a transversely-reciprocating slide equipped with a rack engaging said pinions.

19. In a machine of the character set forth, the combination with strand-wire-feeding mechanism, of a plurality of revolute reciprocable stay-wrappers having channels for the strand-wires and equipped with pinions, and a transversely-reciprocating slide equipped with racks operating upon said pinions and with cams for reciprocating the wrappers, for the purpose set forth.

20. In a machine of the character set forth, the combination of a driving-shaft, strand-wire-feeding mechanism connected with said shaft, a transversely-reciprocable slide actuated from said shaft, a plurality of stay-wrappers, means connected with said slide for rotating said wrappers, and means connected with said slide for reciprocating said wrappers, for the purpose set forth.

21. In a machine of the character set forth, the combination of a plurality of stay-wrappers equipped with pinions, alternate pinions

being ranged between different transverse planes, a transversely-reciprocating slide equipped with racks engaging said pinions, a cam carried by said slide, a longitudinal slide actuated by said cam in one direction and connected with alternate wrappers, a second cam carried by said transverse slide, and a second longitudinal slide actuated by said second-named cam in the direction opposite the direction of movement of said first-named longitudinal slide, substantially as and for the purpose set forth.

22. In a machine of the character set forth, the combination of a suitable frame, a drum journaled at the front end of the frame, strand-wire-coiling mechanism in the rear of said drum, a driving-shaft geared to said drum and said coiling mechanism, a plurality of stay-wrappers located in the rear of said coiling mechanism and having channels for the strand-wires, a transverse slide actuated from said driving-shaft and having cam connection with the front ends of the wrappers and rack-and-pinon connection with the wrappers, and a take-up drum at the rear end of the machine actuated from said driving-shaft, for the purpose set forth.

23. In a machine of the character set forth, the combination of a plurality of wrappers, a slide moving transversely with relation thereto and serving to rotate said wrappers, a longitudinal rock-shaft, and stay-shifters actuated by said rock-shaft, for the purpose set forth.

24. In a machine of the character set forth, the combination with strand-wire-feeding mechanism, of means for feeding stay-forming wire parallel with and adjacent to a marginal strand-wire, a rotary severing device, a plurality of stay-wrappers, one of said wrappers having its operative end located in a transverse plane removed from the transverse plane in which the operative end of said severing device is located, a shifter operative to transfer the stay from the severing mechanism across the first strand-wire, a stationary member serving to engage that portion of the stay which projects beyond the operative end of the first wrapper, thereby to bend said end at right angles to the body of the stay, and additional shifters operative to transfer the successively-unused portions of the stays from strand-wire to strand-wire, for the purpose set forth.

25. In a machine of the character set forth, the combination of a plurality of rotary reciprocating stay-wrappers having stay-engaging hooks occupying successively-advanced planes, means for delivering a stay to the first hook and bending one end portion of the stay at right angles to the main portion thereof, a plurality of transversely-reciprocating shifters equipped with hooks for successively engaging the angle of each stay and drawing

upon the stay so as to bring the angle thereof into position to be engaged by the next successive hook, and means for simultaneously actuating said shifters, for the purpose set forth.

26. In a machine of the character set forth, the combination of a frame having members affording guides for stays, a plurality of stay-wrappers equipped with rotary stay-carriers, and a plurality of reciprocating stay-shifters operating to slide the unused portions of the stays from rotary carrier to rotary carrier, for the purpose set forth.

27. In a machine of the character described, the combination of a frame having transverse guides upon which stay-wires may be slid, a plurality of stay-wrappers equipped with channeled stay-carriers projecting above said guides, and a plurality of stay-shifters having channels complementary to the channels in said rotary carriers, for the purpose set forth.

28. In a machine of the character described, the combination of a frame having a surface over which stays may be slid, strand-wire-feeding mechanism, a plurality of stay-wrappers having channels for receiving the strand-wires and equipped with rotary stay-carriers having channels parallel with the channels for the strand-wires, hooks on the wrappers for engaging the stays at their angles, and stay-shifters moving over said surface of said frame and having channels complementary to the channels in the rotary carriers, for the purpose set forth.

29. In a machine of the character set forth, the combination with strand-wire-feeding mechanism, of a plurality of stay-wrappers having operative ends occupying successively-advanced positions, a plurality of stay-shifters, and a tension device for the stays adjacent to the operative ends of the wrappers, for the purpose set forth.

30. In a machine of the character set forth, the combination with strand-wire-feeding mechanism, of a plurality of stay-wrappers, a plurality of stay-shifters, and tension-rings through which the operative ends of the wrappers extend, for the purpose set forth.

31. In a machine of the character set forth, the combination of a plurality of intermediate rotary wrappers equipped with rotary stay-carriers and with tension devices for the stays, and a marginal wrapper having a more rapid rate of rotation than said intermediate wrappers, for the purpose set forth.

32. In a machine of the character described, the combination of two marginal rotary stay-wrappers having opposite movements of rotation, a plurality of intermediate rotary stay-wrappers having slower movements of rotation than the marginal wrappers, and stay-shifters, for the purpose set forth.

33. In a machine of the character set forth, a marginal stay-wrapper equipped with a head

g^7 provided with a hook g^8 , a stationary member H^6 , means for delivering a stay parallel with and adjacent to said wrapper, and with one end projecting past the member H^6 , and a stay-shifter operative to transfer said stay and bend the same in passing the member H^6 , thereby to bring the transverse portion of the stay into the grasp of said hooks, for the purpose set forth.

34. In a machine of the character set forth, a marginal wrapper equipped with a wrapping-head g^{11} provided with an undercut hook g^{12} , and an open tension-ring h^{15} receiving the portion of said wrapper adjacent to said head, for the purpose set forth.

35. In a machine of the character set forth, mechanism for coiling the strand-wires, comprising a plurality of rotary members equipped with rollers having axes arranged at angles to each other, for the purpose set forth.

36. In a machine of the character described, mechanism for coiling the strand-wires, comprising a plurality of tubular shafts geared together and through which the strand-wires pass, said shafts having cut-away portions whereat they are equipped with grooved rollers for receiving the wires, the axes of said rollers being arranged at angles to each other, for the purpose set forth.

37. Mechanism for coiling strand-wires comprising a plurality of parallel tubular shafts equipped with sprocket-wheels, a sprocket-chain passing over sprocket-wheels having axes parallel with said shafts and engaging said first-named sprocket-wheels, and grooved rollers carried by each shaft and having their axes at angles to each other, each shaft being cut away, for the purpose set forth.

38. In a machine of the character set forth, the combination with a plurality of rotary wrappers having channels for receiving the strand-wires and equipped with means for wrapping the stays about the strand-wires, of removable perforated centering-blocks at the operative ends of said wrappers, for the purpose set forth.

39. In a machine of the character set forth, the combination with strand-wire-feeding mechanism, of a plurality of wrappers having operative ends located between successively-advanced planes, and endless-chain mechanism serving to maintain the strand-wires in their proper courses while the stays are being applied, for the purpose set forth.

40. In a machine of the character set forth, the combination with strand-wire-feeding mechanism, of a plurality of tubular stay-wrappers having operative ends lying between successively-advanced transverse planes, stay-shifters, and mechanism for separating the marginal strand-wires after the stays have been applied, thereby to straighten the stays, for the purpose set forth.

41. In a machine of the character set forth,

the combination with strand-wire-feeding mechanism of a plurality of tubular stay-wrappers having operative ends lying between successively-advanced transverse planes, stay-shifters, and endless-chain mechanism for separating the marginal strand-wires after the stays have been applied, said mechanism comprising endless chains located adjacent to the paths of the two marginal strand-wires and grappling-hooks connected with said chains, for the purpose set forth.

42. In a machine of the character set forth, the combination with strand-wire-feeding mechanism, of a plurality of stay-wrappers having operative ends located between successively-advanced transverse planes, endless chains located adjacent to the paths of the marginal strand-wires, grappling-hooks connected with said chains, and cams guiding the operative portions of said chains, for the purpose set forth.

43. In a machine of the character set forth, a take-up drum comprising a shaft having a joint near one end thereof, drum-sections pivotally supported at one end near said joint, a longitudinally-shiftable sleeve, and a hand-lever linked to said sleeve and pivotally joined to said shaft, for the purpose set forth.

44. In a machine of the character set forth, a take-up drum equipped with a longitudinal rock-shaft provided with hooks, and means for securing said rock-shaft with the hooks projecting and rotating said rock-shaft to sheath the hooks, for the purpose set forth.

45. In a machine of the character set forth, the combination of means for feeding stay-forming wire, said means including a gear-train provided with means for permitting the feed-rollers to stop at intervals while the driving-gear continues to rotate, and a rotary wire-severer and stay-carrier, for the purpose set forth.

46. In a machine of the character set forth, the mechanism J, comprising a rotary stay-carrier equipped with a cutter and with a plurality of longitudinal grooves, and means for directing wire into said longitudinal grooves, for the purpose set forth.

47. A rotary wire-severing and stay-carrying device, comprising a rotary shaft equipped with longitudinal channels and provided near one end with a cutter, a fixed member provided with a channel into alignment with which said first-named channels may be brought, and a tubular cutting member at said second-named channel, for the purpose set forth.

48. Wire-cutting and stay-carrying mechanism comprising a rotary shaft equipped with longitudinal channels and with transverse circumferential channels, a knife carried by said shaft, a stationary knife co-operating therewith, and means for directing a wire into said channels as they are brought in turn into registration therewith, in combination with a

shifter equipped with stay-engaging means moving through said transverse channels, for the purpose set forth.

49. The combination of strand-wire-feeding mechanism, a plurality of wrappers with axial channels for the strand-wires and equipped with non-axial stay-receiving channels, a frame having a surface upon which the stays may slide in the shifting operations, a rotary severer and stay-carrier having transverse grooves, frame projections extending into said grooves and onto which the stays may slide, and stay-shifters, including one having a traverse crossing said severer and stay-carrier, for the purpose set forth.

50. In mechanism for cutting wire into stays and delivering the stays to a shifter, the combination of a rotary shaft supplied with longitudinal grooves and with a cutter revolving with the shaft, and a stationary cutter coacting with said first-named cutter, the cutting-plane being adjustable, whereby the length of the stays may be varied, for the purpose set forth.

51. In mechanism for cutting wire into stays and delivering the stays to a shifter, the combination of a rotary shaft supplied with a non-axial longitudinal groove and with a cutter revolving with said shaft, a coacting stationary cutter, a stationary bearing, and a reduced end on said shaft extending through said bearing and provided with a collar to prevent separation of said cutters, substantially as and for the purpose set forth.

52. In a machine of the character set forth, the combination with strand-wire-feeding mechanism, of means for simultaneously weaving a plurality of independent stays in parallel transverse relation upon the strand-wires, said means including devices which simultaneously wind successive portions of the successive stays upon the successive strand-wires, said means serving to wind a portion of each stay about a strand-wire, pay out the adjacent portion of the stay across the adjacent space, wrap a succeeding adjacent portion of the stay about the next succeeding strand-wire and continue these steps across the fence, for the purpose set forth.

53. In a machine of the character set forth, the combination with strand-wire-feeding mechanism, of means for delivering straight stays parallel with and adjacent to a marginal wire, means for wrapping an end portion of each stay upon a marginal wire, and means for paying out the stays perpendicularly of the strand-wires and wrapping successive parts of the stays about successive strand-wires.

54. In a machine of the character set forth, the combination with continuously-acting strand-wire-feeding mechanism serving to uninterruptedly feed the strand-wires, of mechanism for moving a plurality of stay-wires

with the strand-wires and applying them to the strand-wires while all are in motion, for the purpose set forth.

55. In a machine of the character set forth, the combination with continuously-operative strand-wire-feeding mechanism serving to feed the strand-wires uninterruptedly through the machine, of a plurality of rotary recipro-

cating stay-wrappers, and means for shifting the successively-unused portions of the stays from strand-wire to strand-wire, for the purpose set forth.

CHARLES M. IAMB.

In presence of—

WALTER N. WINBERG,
W. B. DAVIES.
